COMBINED PICTURE FRAME AND STORAGE FILE

Adolph E. Hartmann, Sacramento, Calif.

Application December 26, 1950, Serial No. 202,654

5 Claims. (Cl. 40—158)

This invention relates to card, picture and sign exhibiting, and more particularly to an improved frame construction which adapts it with especial convenience of displaying a picture, drawing, design, map, chart or graph, written report or announcement, or any such material which can be displayed more attractively, conveniently or effectively when mounted within a suitable frame.

For the sake of convenience in terminology, the frame of the present invention will be described throughout this specification and the claims, as being intended for the display of a picture, but it is to be understood that the frame is equally effective and convenient for use with any other decorative or informative matter drawn, painted, printed, or otherwise delineated upon paper, canvas, or other thin sheet material. In other words, I consider that my present invention resides in the frame, and is not concerned with the nature of the matter to be mounted within and displayed by the frame.

An object of my present invention is to provide a frame in the design and construction of which means are provided for the interchange of a picture being displayed thereby for another in a highly convenient manner.

A further object of my invention is to provide a frame within which a picture to be displayed can be mounted in such a manner that not only is the picture appropriately and tastefully framed, but it is also adequately protected just as efficiently as though it were permanently framed, and yet from which the picture can easily and quickly be removed, as for example when it is desired to change the picture for another one.

A further object in this connection is to provide means for facilitating the operation of insertion of a picture into the frame so that not only is the operation of such insertion performed quickly and easily, but also in such a manner that danger of harming the picture is minimized.

Another object of the invention is to provide, in a frame of the general character indicated, a suitable mask, or mat having a cutout opening, and, in co-operative association therewith, a flap which serves not only as a guide in arranging a picture in desired position with respect to the mat's opening, but also in retaining the picture in that selected position upon the back of the mat not only during the operation of inserting the mat and picture into the frame, but also for the duration of the period that that particular picture remains on display.

Yet another object of the present invention is to provide in a frame of the character described, means for accommodating more pictures than the one being displayed at any given time, so that it serves as a storage magazine or file within which a relatively large number of pictures may be filed away in convenient and safe storage and from which any one may be selected whenever desired and exhibited by moving it to that portion of the frame in which it is displayed.

2

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

10 Referring to the drawings:

Figure 1 is a perspective view of a combined frame and storage file incorporating the principles of the present invention.

Figure 2 is a vertical sectional view drawn to an enlarged scale with the plane of section being indicated by the lines 2—2 of Figure 1 and the direction of view by the arrows. A portion of the figure is broken away to reduce its size.

Figure 3 is a perspective view drawn to slightly reduced scale as compared to Figure 2, of the mat and positioning flap which constitute important portions of the frame of the present invention and showing the manner of their use in positioning a picture to be exhibited within the frame.

Figure 4 is an enlarged detail view of a portion of the mat and flap of Figure 3. This may be considered a sectional view taken upon the lines 4—4 of Figure 3 with the direction of view as indicated.

Specifically describing that embodiment of my invention that has been chosen for illustration and description herein, the combined picture displaying frame and storage file comprises a frame member indicated in its entirety at 6 and made up of top and bottom rails 7 and 8 respectively and a pair of spaced end members or stiles 9. These four pieces are rigidly interconnected at their ends, preferably in the manner conventionally employed in the construction of picture frames, to encircle a central opening 11 through which a picture may be displayed. The front surfaces of the members 7, 8, and 9 may be plain or provided with suitable ornamentation such as a series of beads 12 extending longitudinally of each of the four members.

The corner of each of the four members 7, 8, and 9 at the intersection of the back face 16 of the inner edge 17 thereof is routed out to present a recess 18 in the back of the frame 6 of slightly greater length and width respectively than the corresponding dimensions of the frame's opening 11, i. e., each of the four frame members 7, 8, and 9 is possessed of a flange portion 19 extending inwards with respect to the frame's opening 11 a short distance beyond the corresponding edge 21 of the recess 18 in the back of the frame.

The back of the recess 18 is closed throughout the major portion of its area by a back plate 26 of rigid or semi-rigid material such as a sheet of relatively thick and heavy cardboard. However, one edge 27 of the back plate 26 does not extend all the way to the corresponding edge of the frame 6 so as to leave a relatively narrow opening 28 leading into the recess 18 from the back of the frame through which a picture to be displayed can be inserted into the recess in a manner to be described in detail hereinbelow.

Preferably before the back plate 26 is affixed in position to the back of the frame, a sheet 31 of glass is placed in position within the recess 18 and preferably the dimensions of this sheet 31 are such at it fits relatively tightly against the edges 21 of the recess 18 so that it tends to remain in position in contact with the after surfaces of the flanges 19.

In co-operative association with the frame 6 is a mask or mat member 32 having a cut-out opening 33. This mat 32 is made of suitable semi-rigid material such as,

preferably, a good grade of cardboard having an attractive finish on its front surface. The edges 34 of the cut-out opening 33 are preferably beveled in accordance with conventional practice in the construction of such mats so as to lend a highly attractive, neat and finished appearance to the assembly when mounted within the frame 6 and having a picture or the like displayed through the cut-out opening 33. A flap 36 is affixed along one of its edges 37 to one of the edges of the mat 32 and in position with the body portion of the flap extending laterally away from the mat 32. Consequently, in order for the body portion 38 of the flap to assume a position against the back of the mat 32 it is necessary to fold the flap double along a fold line 39 parallel to the edge 37 of the flap which is affixed to the mat 32. When so folded, the flap 38 co-operates with the mat 32 to position a picture disposed therebetween with the edges of the picture accurately parallel to the edges 34 of the mat 32 and in selected position of adjustment wherein the edges of the picture are either concealed behind the mat 32 in the event that the picture is of larger size than the cut-out opening 33, or suitably spaced from the edges 34 of the cut-out 33 in the event that the picture is of smaller size than the cut-out opening 33.

To facilitate locating the picture to be displayed in the desired position in back of the mat 32 and with relationship to the cut-out opening 33, that portion 46 of the flap 36 immediately adjacent the edge 37 thereof which is bonded to the back of the mat 32 is provided with a plurality of preferably evenly spaced lines 47 extending parallel to the edge 37. Preferably these lines 47 are $\frac{1}{4}$ " apart and with each a calibration 48 is associated, each of these calibrations being a numeral which will indicate the size of a picture, in inches, which will be centered with respect to the cut-out opening 33 if an edge of the picture is brought into registry with the line 47 with which that particular calibration 48 is associated. For example, the line 47 with which the calibration "8"" is associated should be 4" from the center of the cut-out opening 33 whereas the next line 47 identified by the calibration "8½"" should be $4\frac{1}{4}$ " from the center of the cut-out opening 33, and so on. Hence, if the mat 32 is removed from the frame 6 and then laid face down upon any suitable supporting surface with the flap 38 opened to its extended position (as indicated in Figure 4) and if a picture 51 is then laid face down upon the back of the mat 32, the bottom edge of the picture 51 should be brought into registry with the line 47 which is the calibration 48 the numerical value of which corresponds to the height expressed in inches of the picture, that picture will be centered with respect to the opening 33 of the mat 32. The body portion 38 of the flap 36 should then be folded over the back of the picture 51 forming a pocket against the bottom of which the lower edge of the picture 51 rests so that the mat 32 then can be re-inserted into the frame 6 with the picture 51 securely retained in selected position by its being enveloped between the mat 32 and the flap 36. It is apparent, therefore, that each of the lines 47 represents a fold line along which the flap 36 may be folded with the result that the co-operating mat 32 and flap 36 serve the dual purpose of facilitating insertion of a picture into the frame 6 without damage to the picture, and of retaining the picture 51 in predetermined position with respect to the mat 32 so as to assure that the picture will remain in that exact position chosen by the operator.

In order to facilitate such entry of the mat 32 and a picture 51 carried thereby into the recess 18, I prefer to relieve the top member 7 of the frame 6 by chamfering or beveling the back surface of the frame member 7 to provide a sloping entrance throat 52 leading into the top of the recess 18 as most clearly shown in Figure 2.

Another important feature of the present invention is concerned with the depth of the recess 18, i. e., the distance measured from the forward face of the back plate

26 to the forward face of the glass 31 at the front of the recess 18. Observation of Figure 2 will disclose that this depth is considerably greater than the combined thickness of the glass 31, the mat 32, the picture 51, and the flap 36. This excess space within the recess 18 adds very materially to the utility of the frame of the present invention inasmuch as it provides a convenient file or storage space within which additional pictures can be stored safely and protected against deterioration by light, dust, and the like. Very frequently, a series of pictures of the same size becomes available to the public, such for example as those used as advertising, different pictures being offered at various intervals so as to persuade the buying public to return frequently to secure the next successive picture. These pictures are usually of high artistic value and the present invention contemplates the provision of a convenient and safe place of assembly and storage of such pictures as they issue. As they are collected, one of the pictures can be displayed, the rest being successively interchangeable with that displayed at the front of the frame, so that the subject matter displayed in the frame can be varied to suit the will.

Means are also provided for supporting the frame 6 in display position. A hanger 56 is secured to the back 25 26 of the frame adjacent the top rail 7 and preferably another similar hanger (not shown) adjacent one of the end stiles 9 so that the frame 6 can readily be hung on the wall in either the horizontal or the vertical position. If, however, it is desired to use the frame as an easel 30 resting upon a desk or table, a short piece 57 of doweling may be inserted into a suitable socket 58 provided in the back surface of the lower rail 8, as illustrated in Figure 2. Preferably, a similar socket (not shown) is also provided in one of the end stile members 9 so that the frame 35 also can be supported as an easel in either the horizontal or vertical position.

I claim:

1. A mat for framing a picture comprising a body of sheet material having therein a window, and picture-centering means co-operatively associated therewith comprising a sheet of foldable material affixed along one edge thereof to the back of said body between an edge of the window and the corresponding outer edge of the body, and extending therefrom toward said edge of the body, said foldable sheet having a plurality of spaced parallel graduation lines imprinted thereon parallel to said edge of the window indicating locations for selectively folding said foldable sheet back upon itself to define a picture-centering bight at selected distance from said edges of the window.

2. A mat for framing a picture comprising a body of sheet material having therein a window, and picture-centering means co-operatively associated therewith comprising a sheet of foldable material affixed along one edge 55 thereof to the back of said body between an edge of the window and the corresponding outer edge of the body, and extending therefrom toward said edge of the body, said foldable sheet having a plurality of spaced parallel graduation lines imprinted thereon parallel to said edge of the window indicating locations for selectively folding said foldable sheet back upon itself to define a picture-centering bight at selected distance from said edge of the window and size-indicating calibrations imprinted on said foldable sheet in co-operative association with said graduation lines.

3. A mat for framing a picture comprising a body of sheet material having therein a window and means for centering a picture with said window with the margins of the picture concealed behind said body and the remainder of the picture in registry with and displayed through the window, said aligning means comprising a sheet of foldable material affixed along one edge thereof to the back of said body and extending from said edge away from said window, said sheet of foldable material being reversely folded about a bight spaced from said

window by a distance corresponding to the width of the associated margin of the picture and thereby presenting an abutment stop spacing the associated marginal edge of the picture from said window.

4. A mat for framing a picture comprising a body of sheet material having therein a window and means for centering a picture with said window with the margins of the picture concealed behind said body and the remainder of the picture in registry with and displayed through the window, said aligning means comprising a sheet of foldable material affixed along one edge thereof to the back of said body and extending from said edge away from said window, said sheet of foldable material having a plurality of spaced graduation marks thereon, each indicating the location for a fold line about which to reversely bend the foldable sheet to form therein a bight spaced from the proximate edge of the window by a distance corresponding to the width of the margin of a picture of predetermined size larger than said window and centered with relation to the window.

5. A mat for framing a picture comprising a body of sheet material having therein a window and means for centering a picture with said window with the margins of the picture concealed behind said body and the remainder of the picture in registry with and displayed through the window, said aligning means comprising a sheet of foldable material affixed along one edge thereof to the back of said body and extending from said edge away from said window, said sheet of foldable material having a plurality of spaced graduation marks thereon,

5
